UNITED STATES PATENT OFFICE

154,350

DESIGN FOR A DISPLAY STAND

Felix Van Cleef, Chicago, Ill., assignor to Johns-Manville Corporation, New York, N. Y.

Application March 15, 1948, Serial No. 145,092

Term of patent 14 years

(Cl. D80—9)

To all whom it may concern:

Be it known that I, Felix Van Cleef, a citizen of the United States, residing at Chicago, in the county of Cook and State of Illinois, have invented a new, original, and ornamental Design for a Display Stand, of which the following is a specification, reference being had to the accompanying drawings, forming a part thereof.

In the drawings:

I claim:

The ornamental design for a display stand, substantially as shown.

FELIX VAN CLEEF.
